UNITED STATES PATENT OFFICE.

GEORGE K. CUMMINGS, OF NEW YORK, N. Y.

DESIGN FOR A PRISM-WINDOW.

SPECIFICATION forming part of Design No. 33,669, dated December 4, 1900.

Application filed August 15, 1898. Serial No. 688,623. Term of patent 7 years.

To all whom it may concern:

Be it known that I, GEORGE K. CUMMINGS, a citizen of the United States, residing at New York, in the county and State of New York, have invented and produced a new and original Design for Prism-Windows, of which the following is a specification.

My invention relates to a new and original design for prism-windows, and is illustrated in the accompanying drawings, in which—

Figure 1 is an elevation or front view of a prism-window embodying my said design, and Fig. 2 is a vertical cross-section through the middle of the window.

As shown in the accompanying drawings, my design consists of panes, plates, or lights of parallel prisms represented by the light parallel lines and inclosed within a rectangular parallelogram and separated by a framework represented by double lines and arranged as follows: Within the parallelogram, at the bottom or lower ends, are a row of triangular-shaped prism-lights resting upon their bases. Next above are a row of diamond-shaped prism-lights inclosed within the

two upper sides of the triangular lights. Next above these are a row of elongated hexagonal prism-lights, with the two sides forming the lower end inclosed within the upper sides of adjacent diamond-lights, next a row of diamond-shaped prism-lights, and then another row of hexagonal-shaped prism-lights, then another row of diamond-shaped prism-lights, and at the top a row of triangular prism-lights similar to those in the bottom row, but resting upon their apices and on two of their sides. Extending from side to side on each of the lights in the entire window are parallel prisms. The whole gives the effect of a barred or grated prism or lined window.

I claim—

The design for a prism-window as herein shown and described.

In testimony whereof I have signed my name to this specification in the presence of two subscribing witnesses.

GEORGE K. CUMMINGS.
